TUBE CLEANER

William S. Elliott, Pittsburgh, Pa., assignor to
 Elliott Company, Pittsburgh, Pa., a corporation
 of Pennsylvania

Application July 23, 1932, Serial No. 625,267

6 Claims. (Cl. 15—104.13)

The present invention relates broadly to the art of cleaning tubes, and more particularly to an improved form of tube cleaner for this purpose.

5 Tube cleaners, as at present constructed, are of two general types. Included within the first type are those cleaners which have pivotally mounted cleaning elements adapted to swing outwardly due to centrifugal force and by a series of 10 blows effect the desired loosening of the scale or deposit on the inside of the tube being cleaned. Such elements swing about axes which are at substantially right angles to the longitudinal axis of the tube being cleaned, and the elements 15 are effective similarly to a plurality of hammers, thus exerting a very efficient cleaning action.

Within the second class of cleaners may be included those in which the cleaning elements, while moving outwardly under the influence of 20 centrifugal force, move outwardly in a general radial direction through slots or openings provided for that purpose.

Elements of the first type have been found to be highly efficient for loosening heavy scale deposits and effecting a partial removing thereof. 25 Due to their action, however, they do not thoroughly clean the tube surface, leaving spots of scale. Cleaners of the second type constitute a more efficient cleaning means for such spots, or 30 polishing means for tube surfaces, but a much less efficient heavy scale removal means. These limitations characteristic of the different types of cleaners have made it difficult to satisfactorily clean and polish a tube having a heavy scale 35 deposit thereon without providing two different types of tube cleaners, or subjecting a given tube to repeated action by a single cleaner.

I have found that it is possible to effectively 40 construct a cleaner which embodies the effective cleaning characteristics of the first type and the effective polishing characteristics of the second type with such a small over-all dimension as to make the structure entirely practical. One object of the present invention is to provide a 45 cleaner adapted to serve both as a scale remover and a tube polisher.

I have also found that it is possible in a construction of the general character referred to, to incorporate the two types of elements, both of 50 which are necessarily individually removable, and provide a common keeper for maintaining all of the elements in position.

Another object of the present invention is to 55 provide a combined cleaner and polisher of the character referred to wherein the outward swing-

ing movement of the cleaning elements is controlled in such manner as to be substantially equal to the outward sliding movement of the polishing elements, so that with the parts in operation, polishing of the tube surface to the full 5 extent to which it has been subjected to a cleaning action by the cleaning elements, is insured.

When it is considered that tubes having an internal diameter as large as 4 to 6 inches, or as small as 2 inches, are mechanically cleaned in 10 the general manner set forth, the advantages and necessity of extreme compactness become apparent. In addition to compactness, the cleaner must be of such construction that considerable 15 freedom of movement of the different elements is possible, to enable them to swing or move outwardly in a required manner to effect complete scale removal, and to move inwardly to the extent necessary to permit easy insertion into a corroded tube. Freedom of outward movement, 20 coupled with a considerable range of movement, further enables the various elements to assume any desired angular position relative to the surface being cleaned, thereby adapting the structure to the removing of irregular deposits. 25

In the accompanying drawing, I have shown for purposes of illustration only, a preferred embodiment of my invention. In the drawing—

Figure 1 is an end elevational view of one form 30 of combined cleaner head constructed in accordance with the present invention;

Figure 2 is a longitudinal sectional view along the line II—II of Figure 1, looking in the direction of the arrows;

Figure 3 is a view partly in section and partly 35 in end elevation along the line III—III of Figure 2, looking in the direction of the arrows; and

Figure 4 is a detail sectional view on the line 40 IV—IV of Figure 2, looking in the direction of the arrows.

In accordance with the present invention, there may be provided a cleaner head 2 in the form of a cage or spider comprising a front disk-like mounting 3 and a rear disk-like mounting 4 connected and held in the desired spaced relation 45 by means of arms 5 connecting the disks 3 and 4 adjacent their peripheral portions. In this manner there is provided a mounting cage of coreless construction, or one in which the center portion 6 of the head is entirely unobstructed, as 50 disclosed and claimed for example in the co-pending application of Hugo Bergquist, Serial No. 610,946, filed May 12, 1932.

Formed in the front mounting 3 is a series 55 of equidistantly spaced radially extending open-

ings 7, as illustrated more particularly in Figure 2 of the drawing. Formed in the rear mounting 4 is a similar series of radially disposed openings 8 which differ from the openings 7 only in the fact that the openings 7 extend completely through the front mounting 3 while the openings 8 extend only partly through the rear mounting 4, as will be apparent from Figure 2 of the drawing.

10 Projecting rearwardly, or secured to the rear mounting 4 is a hub 9 provided with internal threads 10, which are either right-hand or left-hand depending upon the direction in which the cleaner is to rotate. In the embodiment illustrated in the drawing the structure rotates in a clockwise direction as viewed in Figure 1, and therefore the threads 10 are right-hand so that when the driving shaft, which is provided with a threaded male member, is engaged with the threads 10 and the structure rotated, the rotative movement will tend to tighten the parts.

15 The head 2 is adapted to carry the radially moving cleaning and polishing elements before referred to. Each of these elements preferably 20 comprises an individual pin 11, the total number of pins corresponding to the number of slots or openings 7 or 8. Each of the pins is of such length so that when slipped into the position illustrated in Figure 2 through the openings 7, 25 the front ends 12 of the pins will not project beyond the face of the front mounting 3. During this assembling operation there are alternately slipped into position on each of the pins, cutting or polishing elements 14 and washers 15, 30 these being of such construction that they may rotate freely on the pins, or rotate with the pins in the openings 7 and 8. In the illustrated embodiment, I have shown two such cutting or polishing elements 14 on each of the pins, the head 40 and elements 14 being properly proportioned to this end.

25 The assembly of the cleaning and polishing elements having been completed, a keeper 16 in the form of a disk is slipped endwise into position over a projection 17 on a hub 18, thereby forming an end closure for the openings 7 and preventing endwise movement of the pins 11 out of the head 2. Thereafter a cleaning head 19 having a threading extension 20 is threaded into the opening in the hub 18, the projection and opening also having right-hand threads so that rotation of the head 2 in the direction referred to will tend to tighten the heads 2 and 19.

30 The head 19 is of such dimensions as to engage the keeper 16, if used, and prevent removal thereof. Formed in its outer periphery is a series of equi-distant slots 21 each having formed in each side thereof a key-way 22 of such contour as to receive and interlock with a rounded head 23 on a pin 24. Before the head 19 is slipped into position, a series of cleaning elements 25, corresponding in number to the number of the slots 21, is fitted into position.

35 Each of these cleaning elements comprises a generally conical cutting and hammering disk 26 rotatably mounted on a pin 27 having an enlarged head 28 at the front end thereof. Each pin extends through its disk 26, thence through a washer 29 and into and partly through a bearing 30. The bearings 30 are of such dimensions as to fit within the slots 21, as will be apparent more particularly from Figure 2 of the drawing. The pins and the parts carried thereby having been assembled with the bearings 30, the pins 24 40 are moved transversely through the bearings 30

in such manner as to engage slots in the pins 27 so as to interlock the pins 27 with the bearings 30 and prevent movement outwardly thereof or to the right as viewed in Figure 2 relative to the bearings. The complete assemblies are then slipped endwise from the left, viewing Figure 2, into the slots 21 and key-ways 22. Locking pins 31 are then slipped into the key-ways 22 and into engagement with the heads 23 on the pins 24 so that when the head 19 is threaded into position the ends of the locking pins 31 will abut against the keeper 16 and hold all of the parts against movement. The construction described in this paragraph is described and claimed in my Patent No. 928,432, granted July 20, 1909. 15

20 The shape of the bearings 30 is such that they may swing outwardly into the position illustrated in the upper portion of Figure 2, or inwardly into the position illustrated in the bottom portion of this figure. It will be noted that in the outer position they extend outwardly to the same extent as the elements 14 in the head 2 when in their outer position, and that when inwardly they correspond to the inward position of the elements 14. Thus, the composite tool may be readily moved into position within a tube. Due to the coreless character of the head 2, the elements 14 may be of a maximum diameter to provide a large number of teeth and therefore maximum life, while at the same time having a maximum movement inwardly and outwardly of the head 2 without interference. 25

30 In actual use, the cleaning elements 25 will swing outwardly about the transverse axes of the pins 24 and subject the scale to a series of hammer-like blows effective for loosening and removing the major portion of the scale or deposit. As the cleaner progresses through the tube, the portion thereof previously subjected to the action of the elements 25 will be engaged by the elements 14 effective for removing any remaining scale and smoothing and polishing the inside of the tube surface. Since the elements have coordinated movements in both an outward and an inward direction, it will be apparent that the elements 14 may smooth or polish to the full diameter that the elements 25 are capable of cleaning. 40

35 By reason of the construction described, the cleaning head 19 serves as a locking means for the pins which carry the polishing elements of the head 2, and the head 2 constitutes a carrier and driving means for the head 19 so that both heads rotate in operation about a common axis. It thus appears that the front set of cleaning elements 25 are mounted on a common pivot plane and are circularly spaced with respect to the frame and that the rear pairs of elements 14 are also mounted on a common cross-sectional plane and are circularly spaced with respect to the frame. The combined action of the cleaning and polishing elements is such that when the tool has once been moved through a tube, the deposit is completely removed and the tube surface left in the desired condition for re-use. 50

45 By reason of the provision of a rigid head carrying freely radially outwardly swingable cleaning elements and cleaning elements freely outwardly movable as a whole a positive cooperation is obtained between the respective cleaning elements which very effectively accomplishes the desired purpose. The first mentioned cleaning elements pass through the tube and break off by hammer-like blows the heavy deposits or encrustations, and the second mentioned cleaning 55

elements remove the residue and polish the tube wall. As all of the cleaning elements are mounted in a rigid head, they positively co-operate in controlled relationship to clean the tube, the two sets of cleaning elements following along directly behind one another, thus insuring effective operation of both, which would not be insured with a flexible head. Preferably the outward limit of movement of all of the cleaning elements is substantially the same, which further insures effective cleaning of the tube, as if one set of elements had an outward limit of movement less than the other set the latter would have a more pronounced effect and the former would be relatively ineffective.

The front pivoted set of cleaning elements strikes heavier, harder blows than the succeeding set of bodily movable cleaner elements, as explained in the early part of this specification; both because the front arms are pivoted while the back arms are bodily movable, and because of the greater weight of the front arms, as shown.

Another peculiar and unexpected advantage of this particular arrangement of both sets of cleaner elements has been found in actual practice to be that when the proper speed of rotation is imparted to such a head, the centrifugal force exerted on the rear set of bodily movable cleaning elements tends to keep the head centered within the tube without injuring the tube. Thus, the tendency of the swinging cleaner elements to move the head sidewise when they strike projections of scale material located eccentrically or at one side of the tube; is resisted and at least in part corrected by the rear bodily movable cleaner elements. Also, gravity tends to move the head as a whole toward the bottom surface of the interior of the tube and this also is similarly resisted by the rear bodily movable set of arms when actuated by centrifugal force. Eccentric positions of the cleaner head as a whole are thus resisted or overcome.

While I have herein illustrated and described the preferred embodiment of my invention, it will be understood that changes in the construction and operation herein illustrated and described may be made without departing either from the spirit of the invention or the scope of my broader claims.

I claim:

1. In a tube cleaner, a rotatable head having separable portions, radially outwardly swinging cleaning elements carried by one portion of said head, and radially outwardly sliding cleaning ele-

ments carried by another portion of said head, said portions having common means so constructed and arranged as to permit upon separation thereof assembly and disassembly of the cleaning elements and their respective portions of the head.

2. In a rotatable tube cleaner, a polishing head having cleaning elements therein mounted for radially outward sliding movement, a cleaning head secured to said polishing head, cleaning elements carried by said cleaning head and mounted for radially outward swinging movement therein, said cleaner including common means between the two heads constructed and arranged to keep the cleaning elements in position therein when the polishing head and cleaning head are connected together.

3. Tube cleaner construction, comprising a rotatable cleaning head carrying cleaning elements pivotally mounted for radially outward movement, a polishing head carrying cleaning elements slidably mounted for radially outward movement, and common means between the two heads effective upon assembly of said heads for maintaining said first-mentioned cleaning elements in place with respect to the cleaning head and said second mentioned cleaning elements in place with respect to the polishing head.

4. A rotary tube cleaner head having a rigid frame, said frame having a front set of cleaning elements pivoted thereto, and a rear set of bodily movable cleaning elements having guides which allow outward or radial movement therein under centrifugal force, and common means for holding all said elements in position in the frame.

5. A rotary tube cleaner head having a forward set of pivoted pins and a rearward set of slideable pins, the pins of both sets carrying cleaning elements, and being arranged to move substantially in radial directions, and common means for maintaining all of said pins in position.

6. A rotary tube cleaner head comprising front and rear separable sections, a set of cleaning elements, bearings pivotally mounting said set in the front section, a set of bodily movable cleaning elements, bearings mounting said second-mentioned set in the rear section to allow outward movement under centrifugal force, a common rigid locking device for keeping the bearing of both sections in position, and locking means co-operating with said locking device for aiding in maintaining the bearings of one of said sections in position.

WILLIAM S. ELLIOTT.
